[57] CLAIM

The ornamental design for a vehicle step cover, as shown and described.

DESCRIPTION

FIG. 1 is a top plan view of the preferred embodiment of a vehicle cover showing our new design;

FIG. 2 is a front elevational view thereof;

FIG. 3 is an end elevation view thereof, the opposite end being a mirror image of that shown;

FIG. 4 is a rear elevational view thereof; and,

FIG. 5 is a bottom plan view thereof.
